FIG. 5.

UNITED STATES PATENT OFFICE

2,450,518

AIR HEATER FOR CASTINGS

Alexander M. Lister, Philadelphia, Pa.

Application March 18, 1944, Serial No. 527,066

5 Claims. (Cl. 263—19)

1

This invention relates generally to the class of furnaces and pertains particularly to an improved mold drier.

A principal object of the present invention is to provide an improved drying furnace designed for the production of hot air to be used in the drying of various types of molds such as are used in casting, the furnace being designed primarily for the use of coke as a fuel, although it is not necessarily confined to the use of this particular fuel, and it is so constructed that the maximum heating effect of the fuel will be obtained and may be discharged either horizontally or downwardly from the furnace structure into suitable conducting pipes by which the heated air can be carried directly into the molds and mold flasks.

A further and more specific object of the invention is to provide an improved hot air furnace structure designed for the drying of molds and castings wherein a novel arrangement of baffle walls is provided to form opposite sides of the fire chamber and to effect the desired circulation of air from an inlet, downwardly and upwardly through the fire chamber grate and from the upper part of the chamber to lateral and downwardly directed outlets.

Still another object of the invention is to provide an improved hot air furnace structure for the purpose stated, in which the top or roof is readily removable and fire brick baffle walls forming opposite sides of the fire chamber are set in a novel manner whereby they may be easily and quickly inserted and removed when and as desired.

The invention will be best understood from a consideration of the following detailed description taken in connection with the accompanying drawings forming a part of the specification, it being understood, however, that minor changes and modifications may be made in the structure so long as such changes and modifications mark no material departure from the salient features of the invention as expressed in the appended claims.

In the drawings:

Figure 1 is a view in top plan of a mold drying or hot air furnace constructed in accordance with an embodiment of the present invention.

Figure 2 is a view in elevation of the air discharge end of the structure.

Figure 3 is a vertical longitudinal section taken substantially on the line 3—3 of Figure 1, the view being on an enlarged scale.

Figure 4 is a transverse section taken substan-

tially on the line 4—4 of Figure 1, the figure being on an enlarged scale.

Figure 5 is a fragmentary section taken on the line 5—5 of Figure 4.

Figure 6 is a detailed section on the line 6—6 of Figure 3.

Figure 7 illustrates a slight modification in the top or roof construction.

Referring now more particularly to the drawings it will be seen that the heater structure is of elongated rectangular form and comprises the vertical side walls 10 and the end walls 11 and 12 which may be referred to respectively as the front and rear walls. These latter walls are formed integrally with supporting legs 13 by which the bottom of the furnace structure is maintained at the desired height or level above the supporting floor F.

The bottom wall of the structure is designated 14 and this wall is initially supported upon suitable lugs 15 which may form a part of the end walls before the several walls are permanently secured together as by welding and the like.

In order to facilitate the assembly of the structure the side and end walls are provided with the cooperating ears 16 which are joined by the bolts 17. While the structure may be maintained in assembled relation by means of these bolts secured ears it is contemplated to weld the side, end and bottom walls together so as to form the body as a unitary structure.

The bottom wall 14 is provided with a cleanout opening 18 which is bordered at its longitudinal sides by the upstanding guide flanges 19 and 35 which is normally closed by the sliding clean-out door 20 which, as shown in Figure 4, extends through a suitable slot 21 in one side wall and is formed as at 22 to provide the finger hold whereby it may be readily shifted outwardly when it is desired to open the clean-out opening. The purpose of this cleanout opening will become apparent as the description of the invention proceeds.

Adjacent the front end of the structure the bottom wall 14 has integrally formed therewith the downwardly extending hot air discharge nipple 23 which is flanged as indicated at 24 to facilitate the convenient connection therewith of a pipe, not shown, for leading off the hot air to a mold. This nipple is here shown as being closed by a plug 25 which will be employed when the horizontally discharging nipple 26, which forms a part of the front end wall structure, as shown in Figure 3, is employed for leading off the hot air to a mold or to molds. Instead of using a single 55 lead-off pipe connected with either the nipple

23 or the nipple 26, there may be employed a manifold, not shown, from which a number of pipes may be extended to different molds.

Encircling the interior of the structure adjacent to the floor or bottom wall 14 is a flange 27 which, immediately forwardly of the clean-out opening 18 is broken where it extends along the side walls, as indicated at 28. These breaks or openings in the flange 27 where it extends along the side walls, allow for the extension through to the bottom or floor 14 of a fire brick baffle wall 29 which extends across the width of the furnace structure and is maintained in position by the guide lugs 30 carried in spaced relation upon the side walls as shown in Figure 3.

The floor or bottom 14 below the side portions of the flange 27 carries upstanding lugs 31 adjacent the side walls between which the lower part of the forward baffle wall 29 positions.

In spaced relation with the baffle wall 29 and adjacent to the rear wall 12 of the structure a rear transverse baffle wall 32, of fire brick, extends transversely of the furnace structure and is supported upon the side portions of the flange 27, as shown in Figure 3, being maintained in the desired vertical position by the lugs 33 carried by the side walls. Since the forward wall 29 drops down lower than the rear wall 32 it will be readily seen that the top of the forward wall is at a lower elevation than the top of the rear wall and this allows for the free passage across the top of the forward wall of air flowing upwardly from the space between the walls, which forms the fire box and which is designated 34. Between the rear fire box wall 32 and the rear furnace wall 12 a relatively narrow space 35 is provided which receives fresh air which is discharged through the wall 12 by way of the inlet 36, such air being preferably introduced under pressure by a blower 37, here shown as supported upon the bracket or shelf 38 which is mounted upon the outer side of the rear wall 12. The air inlet pipe 36 has a suitable damper 39 therein by means of which the quantity of air introduced may be readily regulated.

Since the rear fire box wall 32 is supported by the flange 27 above the floor 14 it will be seen that the introduced air will flow downwardly and under the rear fire box wall and upwardly through the lower part of the fire box.

Between the fire box walls 29 and 32 the side portions of the flange 27 function as a supporting means for the transverse grate bars 40 and it will be noted that these bars lie over the clean-out opening 18 and plate or door 20.

The space 41 between the front fire box wall 29 and front wall of the furnace structure receives the hot air and gasses from burning fuel lying in the fire box upon the grates 40 and this space has the lead off nipples 23 and 26 opening thereinto as shown.

Encircling the interior of the structure adjacent the top and above the walls 29 and 32 is the flange 42 which in the side wall portion has the breaks or recesses 43 and 44 therein which are respectively above the baffle walls 29 and 32 and permit the removal and insertion of these walls in a manner which will become readily apparent upon reference to Figure 3.

The top flange 42 within the furnace structure, functions as a support for the top or roof of the furnace which is generally designated 45. This roof is of metal, preferably cast iron like the side walls and floor of the structure and is slightly transversely arcuate as shown in Figures 3 and

4 and has the integral encircling side and end wall flange 46.

As shown in Figures 2 and 4 the side portions of the flange 46 of the roof structure are straight or unbroken whereas in the slight modification shown in Figure 7 the side wall flange would be designated 46' has the short vertical upper portion 46a and the longer lower portion 46b which is angled inwardly as shown.

10 The inner surface of the roof structure is covered by suitable fire brick 47 and it will be readily seen that by transversely arching the roof structure and by providing the inwardly angled side and end flanges such brick structure will be firmly retained in position.

15 As it is readily seen in Figures 4 and 7, the roof structure fits into the top of the furnace between the side, front and end walls and rests upon the top interior flange 42.

20 In order to facilitate the introduction of fuel, a section of the roof structure may be cut out to form the door 48 which is hinged to the adjacent main body portion of the roof as indicated at 49 and is provided with a suitable hand hold 50 to facilitate opening the door.

25 In order to facilitate lifting the roof from the furnace structure, when necessary, lift rings 51 are provided and where it may become necessary to lift the entire furnace structure from one position to another, the hanger loops 52 are provided which are welded or otherwise suitably secured to the furnace side walls.

30 While no lining has been shown for the side and end walls and for the bottom or floor of the furnace it will be readily appreciated that such lining may be employed if desired.

35 The heater structure of the present invention may be used for many purposes. By putting it directly over a mold and using the downward outlet or nipple 23, if the molder when ramming up his cope, puts a plug in to allow a pipe to go into the deepest part of his mold so that when the heat is turned on it is forced to the lowest part of the mold, the remainder of the hot air rises and dries out the remainder of the mold. This applies to large pit molds, or molds made in large plants. It is always advisable to place the cope over the drag so that both may be dried at the same time.

40 50 When the pipe from the heater enters the mold at its lowest point a plate or a piece of metal is placed so that when the heat is forced down it protects the face of the mold from burning and also helps to deflect the hot air to the other parts of the mold.

55 By using the side outlets or the outlet at the front end of the structure, the cheeks of the mold may be dried by causing an elbow to deflect the heat upward or in a direct line from the heater by using a straight pipe and allowing it to go in on the end of the flash between the cope and drag, thereby using a direct flow of hot air to circulate through the mold. As previously stated either a single pipe may be connected to the nipple 26 or there may be used a manifold whereby a number of smaller pipes may be employed to dry a number of jobs at one time.

60 70 The outlet 26 may be put against a core oven by making a suitable opening through the wall of the oven and placing a pipe therein. In this way the hot air is forced into the oven and it dries the cores faster and makes a clean oven.

75 The present structure can also be employed for drying sand for sand blasters, especially where it

is necessary to use fine silica sand for very fine work.

While the invention is not limited to any particular size, a convenient size is approximately 48 inches long, by 31 inches wide by 45 inches high. In a structure of this kind where coke is used as fuel an average wheelbarrow load is sufficient for operation of the furnace for a working day.

In foundries where molds are dried with charcoal the present furnace, because of its novel construction, may be operated more economically than any other known type of furnace and the use of this fuel provides an ash free air which produces a clean mold and a uniformly dried mold.

The present structure is also designed for use in drying loam molds as well as those of sand.

It will be readily apparent that because of the novel construction of the furnace structure ash may be easily and quickly removed therefrom without materially interfering with the flow of air and also the fire brick baffle walls forming two sides of the fire box may be easily and quickly removed or inserted through the top of the furnace structure after the roof has been removed.

I claim:

1. An air heating furnace of the character stated, comprising a rectangular structure having side, end and bottom walls and a removable top wall closing the top of the structure, means for introducing air through one end wall, means for carrying off air from the structure at the other end wall, a flange encircling the interior of the structure adjacent to the bottom wall and carried by the end and side walls, said flange in the side wall portions having oppositely positioned breaks therein, a pair of transversely extending fire resistant walls within the structure, one of said walls being adjacent to the air outlet and extending downwardly through the said breaks in the flange and resting upon the bottom wall, the other one of the transverse walls being supported upon the opposite side wall portions of the flange adjacent the end wall having the air admission means therein, the space between said transverse walls forming a fire box, a grate structure supported in spaced relation with the bottom wall in the lower part of said fire box, and said transverse walls being maintained for verti-

cal sliding movement to facilitate removal through the top of the structure when the top wall is removed.

2. An air heater structure as set forth in claim 1 in which the grate structure comprises a plurality of bars supported at their ends upon the side wall portions of the flange lying between said baffle walls.
3. An air heating structure as set forth in claim 10 1 in which the grate structure is supported upon and between the side wall portions of the flange whereby air entering between the said other transverse wall and the adjacent end wall will flow beneath the said other transverse wall to the under side of and up through the grate.
4. An air heater structure of the character set forth in claim 1, with a flange encircling the interior of the structure adjacent the top and functioning as a supporting means for the removable top wall, the last mentioned flange having the side wall portions thereof provided with recesses in the vertical planes of the transverse walls to facilitate the removal upwardly of said transverse walls from their working positions.
5. An air heating structure as set forth in claim 20 1, with a flange encircling the interior of the structure adjacent the top and provided in the side wall portions thereof with recesses in the vertical planes of said transverse walls to facilitate vertical movement of the partition walls for insertion and removal, the said top wall having a depending encircling flange, fire resistant material covering the under side of the top wall and maintained in position by said flange, and said top wall resting upon the second mentioned flange carried by the structure walls.
